VINCENT G. APPLE, OF DAYTON, OHIO

WOUND ELECTRICAL DEVICE AND METHOD OF MAKING IT

Application filed March 1, 1928. Serial No. 258,398.

My invention relates to improvements in the structure of wound electrical devices and in the method of retaining the windings thereon.

5 One of the objects of my invention is to provide a structure wherein the winding and the connection between the winding and the terminals and the terminals themselves, all are imbedded in a mass of insulating material, which cements the winding to the core and keeps it rigid, to the end that deterioration incident to vibration of the parts, where yielding windings and flexible leads are employed, will be eliminated.

15 Another object is to so enclose the conducting elements of the structure as to effectually protect them against deterioration from the action of oil, moisture, corrosive gases, etc., to which wound electrical devices of the conventional type are subject.

25 Still another object is to eliminate the frame usually required in wound electrical devices by forming a frame out of the same mass of insulating material within which the winding is imbedded.

Still another object is to secure attaching means for the device and terminals for the winding to the body of the structure in such a manner that they will materially strengthen the structure by tying the insulation mass to the body which carries the winding.

30 Still another object is to provide a simple and efficient method of procedure to carry the other objects into effect.

35 I attain all the foregoing objects by the structure and method hereinafter described, reference being had to the drawing wherein—

40 Fig. 1 is a longitudinal cross section thru an electro-magnet made according to my invention.

45 Fig. 2 is a longitudinal cross section thru the impregnating mold used in making the electro-magnet Fig. 1.

50 Fig. 3 is a longitudinal cross section thru a second mold for adding heavier masses of insulation.

55 Fig. 4 is a cross section thru a transformer built by my method.

Fig. 5 is a cross section thru another electro-magnet built by my method.

Similar numerals refer to similar parts throughout the several views.

The conventional wound electrical device 55 usually comprises one or more coils wound about a core, or other member adapted to carry the winding, the coils being dipped or otherwise impregnated with liquid insulation and baked to make a rigid structure, together 60 with a frame or casing, separately made, to which the wound and impregnated structure may be secured, the terminals for the winding usually being mounted in the frame or casing and loose ends of the coils usually being connected to the terminals. 65

The present invention consists, in part, in adding to the mass of insulation which impregnates the windings so as to form a casing thereof, which will enclose the coils so 70 that no other frame or casing is needed, the terminals, the coils, the connections therebetween, the attaching bolts, etc., all being imbedded in the same substantially continuous mass of insulation, so as to electrically, mechanically and chemically protect the several 75 parts of the structure.

To illustrate my invention Figs. 1, 2 and 3 show an electro-magnet and the method employed to produce it. A magnetizable core 80 10, having upwardly extending poles 11 and laterally extending ends 12 is provided. Bushings 13 of insulating material are driven into holes in ends 12 and terminal posts 14 are driven into bushings 13. Coils 15 are 85 placed over poles 11 and the ends of the wire composing the coils are joined to terminal posts 14 at 16. Attaching studs 17 are entered into suitably positioned holes in ends 12 all substantially as shown, and the structure is 90 ready to have the insulation mass applied.

Where, as in the instant case, the structure is such that the insulation mass is considerably in excess of that required to cover the coils, and is preferably of considerable 95 strength, insulation in two forms is usually employed and molded in two separate operations, a different mold being provided for each operation. This molding procedure is fully described in my co-pending application 100

Serial No. 205,253 and consists briefly of using insulation of considerable fluidity, which may not be readily cured in large masses, for the first operation, to impregnate the winding, 5 to cement it to the core, and to slightly cover the coils and the joints between the coils and the terminals, so that afterward plastic molding compounds of lesser fluidity containing fibrous fillers to increase their strength 10 may be safely used and molded to the structure in the greater masses required.

Where, however, the extent and the nature of the insulation required permits molding a single kind of insulation to the finished form 15 in a single operation, the molding is preferably carried out in that manner.

Fig. 2 shows the impregnating mold comprising parts 18 and 19 held together by bolts 20, the wound structure being contained there- 20 in. A very slight space 21 is permitted in the mold around the coils 15 and around the joints 16 between the coils and the terminals, and around a small portion of attaching studs 17. Pipes 22 are held in place by pressing 25 flanges 23 against the mold until the winding is impregnated, when they may be quickly withdrawn and solid plugs substituted in their stead. A vacuum process may be em- 30 ployed wherein one pipe 22 exhausts the air from the inside of the mold and from the interstices of the winding and the other sub-sequently permits the liquid insulation to be drawn into the mold, or the liquid may be 35 poured or pumped in thru one pipe and the other used for a vent until the mold is filled. In either event when the mold is filled, the entire structure, including the mold, core, winding, terminals and attaching screws are 40 baked until the liquid insulation becomes a solid mass, after which the mold is removed.

The structure is then placed in mold Fig. 3 which is made in two parts 24 and 25 and has a vertically movable plunger 26 in part 24. Since the coils and the joint between 45 the coils and terminals have previously been covered with a hard coating of insulating material in mold Fig. 2, no damage to the structure results when plunger 26 is raised and a quantity of loose molding compound 50 is placed under it and forced downward by heat and pressure, by the well known molding process, to fill open spaces 27 and 28 to provide a housing 29 and a base 30 of the insulating material.

Fig. 1 shows the completed electro-magnet encased in the housing of insulation, and whether the insulation has been added to the structure by the two operation process described or by a single operation, it is ap- 55 parent that with the terminals 14 fastened to the core and then imbedded in the insulation mass, and the attaching studs extending thru and beyond the core and into the insulation at both ends, and the coils sur- 60 rounded by a suitably shaped casing of the

insulation as shown, all of the objects hereinbefore set forth have been attained. The terminals 14 extend from the insulation for connection to the external circuit and the attaching studs 17 extend for joining the 70 device to a panel or other structure.

As another embodiment of my invention Fig. 4 shows a longitudinal cross section thru a transformer comprising a core 40 carrying coils 41 and 42, incandescent lamp terminals 43 and 44 for primary coil 41, lamp socket terminals 45 and 46 for secondary coil 42, and a casing of insulation 47 molded in situ to penetrate, surround and support the several parts of the device. The terminals 43, 44, 45 and 46 are attached to the core by bolts 48 which pass thru insulation bushings 49, said bushings also extending thru the terminals to keep one pair of terminals insulated from the other. The coils are joined to the terminals at their points of support on the core as at 50 and 51 so that slight deflection of the terminals during the molding operation will not sever the wire therefrom. The insulation may be applied in one or more operations depending on the nature of the insulation used. The device is adapted to be inserted 80 into a lamp socket to draw current for the primary coil and to have a plug inserted at its lower end for taking current of other voltage from the secondary, though it is obvious that the terminals at either end may be formed at the surface of the insulation mass, into binding posts, slip connections, or 85 whatever form of connector is desired. 90

Fig. 5 is a cross section thru an electro-magnet comprising, a core 60, a coil 61, a grounded terminal 62, an insulated terminal 63, and a cover of insulation 64 surrounding the core, coils, and terminals to protect and bind the structure together. Terminal 62 is pressed directly into a hole in the core, while terminal 63 is pressed into an insulation bushing 65 which is pressed into the core. The coil may be wound in place and its ends joined to the terminals, then the insulation molded in place to further fix the terminals as well as the other parts of the structure. Since the structure 100 shown in Fig. 5 does not require large masses 105 of insulating material of great strength, the insulation is preferably applied in a single 110 operation.

While the drawing and description show and describe relatively few embodiments of my invention, it is readily conceivable that the principles involved may be advantageously applied in producing wound electrical devices of almost any character, and while the several structures shown all embody a core of magnetic material it is obvious that the coils may be wound on a hollow member of non-magnetic metal or of insulating material, terminals attached thereto, and the 115 120 125 130 135

mass of insulation molded thereabout, and a magnetizable core afterward separately inserted into the hollow member.

Having described my invention, I aim to more fully define its scope in the following, wherein I claim—

1. An electrical device comprising a member adapted to carry a winding, a winding on said member, terminals for said winding supported on said member, said winding being jointed to said terminals, and a substantially continuous mass of insulating material impregnating and covering said winding and covering the joints between said winding and said terminals.

2. An electrical device comprising a member adapted to carry a winding, a winding on said member, terminals for said winding mechanically joined to said member, but electrically insulated therefrom, said winding being electrically joined to said terminals, and a substantially continuous mass of insulating material impregnating and covering said winding and covering the joints between said winding and said terminals.

3. An electrical device comprising a member adapted to carry a winding, a winding on said member, terminals for said winding supported on said member, said winding being electrically joined to said terminals, and a substantially continuous mass of insulating material impregnating and covering said winding, covering the joints between said winding and said terminals, and cementing said winding to said member.

4. An electrical device comprising a member adapted to carry a winding, a winding on said member, terminals for said winding supported on said member, said winding being electrically joined to said terminals, and molded insulating material impregnating and covering said winding, covering the joints between said winding and said terminals, cementing said winding to said member, and furnishing further support for said terminals.

5. In an electrical device, a core, a winding on said core, terminals for said winding attached to said core, but electrically insulated therefrom, joints between said winding and said terminals, insulating material molded thru and about said core, winding, terminals and joints to prevent relative movement between said parts to injure said joints, and to imbed and further secure said terminals.

6. A wound electrical device comprising a member adapted to carry a winding, a winding on said member, relatively heavy terminals for said winding rigidly affixed to said member, the ends of said winding being joined to said terminals, and a mass of molded insulation extending thru and about the winding and terminals, the free ends of said terminals extending to the surface of

the insulation mass and there being formed like the terminals of an incandescent lamp, so that the current may be applied to said winding by entering said terminals into a lamp socket.

7. An electrical device comprising a member adapted to carry a winding, a winding on said member, a terminal for said winding secured to said member, said winding being electrically joined to said terminal near its point of support on said member, and a substantially continuous mass of insulating material covering said winding and the joint between said winding and said terminal.

8. An electrical device comprising a core, a winding on said core, a mass of molded insulation covering said winding, and attaching means for joining said device and other structures together, said attaching means extending from said core thru and beyond said insulation mass and being roughened where it passes thru said insulation mass so as to serve also as a means to tie said insulation mass to said core.

9. An electrical device comprising a core, a winding on said core, a mass of molded insulation covering said winding and extending further to form a frame for said device, and attaching means for joining said device and other structures together, said attaching means extending from said core thru and beyond said frame, and being roughened where it passes thru said frame to assist in tying said frame to said core.

10. An electrical device comprising a core, a winding on said core, a mass of molded insulation covering said winding, and a terminal for said winding attached to said core and extending thru said insulation mass to the surface thereof to convey current for said winding and to tie said insulation mass to said core.

In testimony whereof I hereunto subscribe my name.
